SAFETY POLE CLIP

Jacob Wilson Lowes, Quill Lake, Saskatchewan,
CanadaApplication June 1, 1939, Serial No. 276,831
In Canada October 15, 1938

1 Claim. (Cl. 278—51)

This invention relates to improvements in safety clips to be attached upon the end of a wagon pole, and a principal object of my invention is to provide a device of the character herein-
5 within described which will enable the neck yoke of a team of horses to be maintained near and above the forward extremity of the wagon pole, thus preventing the possibility of the driving reins becoming caught thereunder.

10 A further object of my invention is to provide a device of the character herewithin described in which the wagon pole is secured positively to the neck yoke of a team of horses, whereby the possibility of accidents occurring due to accidental dropping of said pole, is prevented.

15 A further object of my invention is to provide a device of the character herewithin described which will serve to secure the horses' neck yoke positively to the forward extremity of the pole
20 but which may be quickly and easily released therefrom.

25 A still further object of my invention is to provide a device of the character herewithin described which is of sturdy, simplified structure, which is economical to manufacture and which will not readily become out of order.

With the above more important objects in view and such other minor objects as may appear as the specification proceeds, my invention consists
30 essentially in the arrangement and construction of parts all as hereinafter more particularly described, reference being had to the accompanying drawing, in which:

The figure is a side elevational and partial
35 sectional view of my invention in situ upon a wagon pole.

My invention consists essentially of a partially hollow sheath-like body or casting 1, designed to fit snugly over the forward end of a wagon pole
40 2. The rearward portion of the body is extended integrally into a pair of upper and lower reinforcing arms 3, the ends of which are provided with a pair of drill holes 4 in alignment with a drill hole 5 in the pole 2, through which extends the bolt 6. The body is further secured upon
45 the wagon pole by means of the bolt 7 passing through these members, the upper end of said bolt being curved forwardly and downwardly to be received in a drilled recess 8 upon the upper surface of the body.

50 Formed in the forward extremity of the body 1, is a vertically disposed recess 9 of the configuration illustrated, opening forwardly and upwardly and bounded by the portion 1' of the body and the floor 10 of said recess. A later-

ally extending ring receiving slot 11 is formed across the lower forward extremity of the body 1, passing through the recess 9 at a point just above the floor 10. A latch 12, of the configuration clearly illustrated, is pivotally mounted 5 in the recess 9 upon a pin 13 extending laterally between the side walls of said recess, and is provided with a notch 14 upon the perimeter thereof which is engageable with the lock strap 15 whereby the finger 16 bounding the slot 11', formed 10 therein, may be maintained across the mouth of the slot 11.

The lock strap 15 comprises a strip of metal worked into the configuration illustrated, and movably secured upon the upper surface of the 15 body by means of the upper staple like portion of the bolt 7 passing through the drill holes 17, 18 and the slot 19 formed therein. One end of the strip 15 is formed into a loop 20 to serve as a bearing surface against the notch 14 and is 20 secured to the middle portion of the lock strap by the rivet 21, the forward end of the strip extending over the loop 20 and for a short distance over the upper surface of the latch 12.

With my invention secured upon the end of a 25 wagon pole, the ring suspended from the horses' neck yoke is inserted in the slot 11, the latch 12 turned clockwise until the finger 16 closes thereover, and the lock strap 15 dropped into position such that the end of the loop 20 bears 30 against the notch 14 and prevents the latch from turning back and releasing the yoke ring. To release the yoke ring, it is only necessary to lift the forward end of the lock strap, whereupon the latch may be turned back and the ring released. If it is desired, a line 22 may be attached to the loop 20, of the lock strap, and extended rearwardly to the driver's seat of the wagon, such that in an emergency in which the driver sees fit to release the main trace and to 40 disconnect the horses completely from the wagon, a tug upon said line will serve to unlock the latch 12 and release the horses' neck yoke.

In this manner I have provided a simple, sturdy and easily attachable wagon pole clip which 45 enables the neck yoke of a team of horses to be maintained near the end of the pole, thus precluding the possibility of the reins becoming caught thereunder, and further, in providing a positive connection between said neck yoke and 50 said pole, precludes the possibility of the latter dropping while the wagon is in motion, as is a common cause of accidents with the present type of harness.

Since various modifications may be made in 55

the above invention, and many apparently widely different embodiments of same, made within the scope of the claim without departing from the spirit and scope thereof, it is intended that all 5 matter contained in the accompanying specification shall be interpreted as illustrative only and not in a limiting sense and I desire only such limitations placed thereon as are specifically expressed in the accompanying claim.

10 What I claim as my invention is:

An attachment to the free end of horse drawn wagon poles for preventing the catching of the lines thereunder, comprising in combination, a ferrule encasing said free end, means for securing said ferrule to said pole, a lock housing in the forward end of said ferrule, said latch housing comprising a deep, vertical, open ended recess having an arcuate inner wall, a forwardly projecting underjaw below said recess, a rotary lock

within said recess having a downwardly projecting nose capable of contacting said underjaw and when contacting said underjaw presenting a circular transverse aperture to receive a neck yoke ring, a horizontal and forwardly extending spring latch upon the upper side of said ferrule secured to the rear of said rotary lock, an upwardly projecting abutment having a rearwardly directed, vertical bearing surface upon the upper portion of said rotary lock, the forward end of 10 said spring latch being contiguous with said bearing face when the attachment is in locked position and means for lifting the forward end of said spring latch against the spring tension thereof clear of said bearing surface to permit 15 rotation of said lock and the disengagement of a ring held within said circular aperture.

JACOB WILSON LOWES.
